SMOKING PIPE

John P. Tarbox, Philadelphia, Pa.

Application March 1, 1934, Serial No. 713,558

18 Claims. (Cl. 131—12)

My invention relates to smoking pipes and method of cleansing the same. Such pipes are commonly intended for use in connection with loose tobacco. A special class of such pipes, however, has to do with cigar and cigarette holders or other utilization of tobacco in wrappings or containers. My invention may be applied to any of these.

Its outstanding object is the efficient collection of moisture and other content of the smoke which usually collects within the stems of pipes and the efficient cleansing of the stem of such products.

A further object is the guarding of the stem with a cleansing device against the entry of solid matter from the pipe charge and the efficient ejection of the charge residue and efficient cleansing of the pipe bowl. The latter two results aid materially in guarding the draft members of the pipe against entry of solid matter from the charge.

A yet further object is to maintain open and free from deposit which may obstruct the draft, particularly the opening between the draft portion of the pipe and the bowl but also all other parts of the draft members.

These objects I attain outstandingly by including in the draft connection between the mouthpiece of the pipe and the bowl a displacement type of pump through the chamber of which the draft connection is effected and which displacement pump has a valved connection to atmosphere for the forcible ejection of the contents of the pump chamber to atmosphere. A second valve connection is provided between the chamber and the pipe bowl. In the bowl of the pipe above the pump there is provided in all cases a disc type guard. This guard is axially reciprocable into and out of its guarding position by various means.

The utilization of a pressure force pump for the ejection of the liquid condensate and ash or other solid content of the smoke which is collected by condensation usually in the stem, is the means best known to me at the present time for carrying out the method of my invention which is simply this. A fluid pressure is developed within the liquid content of the pipe and this fluid pressure is utilized to eject the contents themselves.

The drawings represent several of the best embodiments of my invention. Referring to them—

55 Figure 1 is a longitudinal section in the plane

including the axes of the bowl and stem of the pipe of one form of the invention.

Figure 2 is a similar section of another form of the invention.

Figure 3 is a section on line 3—3 of Fig. 2 looking in the direction of the arrows.

Figure 4 is a section of yet another form also in the plane including both the bowl and the stem axes.

Figure 5 is a top plan view of the form of Fig. 4.

Figure 6 is an axial section of still a fourth form.

Figure 7 is a general side elevation showing in dotted lines the application of the invention to pipes having curved mouthpieces and bowls at acute angles to the stems, such as commonly found in curved or depending stem pipes.

Figure 8 is an axial section of a pipe or cigarette or cigar holder embodying the invention of Fig. 6.

Figure 9 is a portion of the section of Fig. 1 showing the parts in an ejecting position.

Figure 10 is a similar view of a portion of Fig. 2.

Figure 11 is a front end view of the form of the invention shown in Fig. 1 with the parts broken away taken on line 11—11 of Fig. 1.

Figure 12 is a section on line 12—12 of the form of invention shown in Fig. 4 showing the section of the front end of the plunger.

Figure 13 is a transverse section through the connection between the stem and mouthpiece of the form of Fig. 1.

Similar reference numerals are used throughout to designate similar parts. The bowl of the pipe is designated 10, the mouthpiece in general 11, the stem in general 12. Intermediate the bowl 10 and the mouthpiece 11 there is used in each of the several forms of the invention a displacement pump designated generally 13 through the chamber of which 14 the draft connection from the bowl 10 to the mouthpiece 11 is effected. This pump may be located anywhere whatsoever and in any attitude between the bowl 10 and the mouthpiece 11 and it may be of any form of displacement pump whatsoever. In the several forms disclosed, however, I have for the sake of convenience located it within and considered it a part of the stem 12.

The pump is illustrated as a reciprocating type of plunger or piston pump utilizing a piston 15 reciprocated longitudinally of the chamber 14 and the chamber 14 is of elongated cylindrical form. Sometimes this chamber is annular in form defined wholly by the circular cross section of the stem as in Fig. 6 or by the cross sec-

tion of the inserted tube 20, as in Fig. 1, and sometimes it is approximately rectangular and formed partly by the walls of the stem or inserted tube and partly by the configuration of the plunger as in Figs. 2, 3 and 4. The piston 15 fits snugly within the chamber so as to move easily therein under all conditions of operation or use of the pipe but yet be substantially or wholly free from leakage as may be desired. The piston 15 is reciprocable within the chamber by means of piston rod 16. In some cases, as in the instance of Figs. 1, 6 and 8, the piston rod 16 is of small cross section located centrally of the circular chamber in the stem, as is more common with piston rods, and in other cases, as in Figs. 2, 3 and 4, this piston rod, designated in these views 16', is enlarged and except for its cut-away portion which opens up the space of the chamber 14, is substantially of the diameter 20 of the piston 15. The chamber is provided at the bowl end with the port 17, as in Figs. 1, 2 and 4, and with a port 44 as in Figs. 6 and 8, through which it connects with the bowl and is provided also either at the bowl end, as in Figs. 1, 2 and 4, 25 with the port 18, or at the mouthpiece end, as in Figs. 6 and 8, with the port 45, which communicates with the atmosphere, one end at least of the chamber is provided with an abutment 19 sometimes (see Figs. 1, 6, 8 and 9) constituting the 30 solid end closure or head of the chamber and sometimes, (see Figs. 2, 3, 4 and 10) in the form of a deflectable head or end closure 19' serving as a scraper with which abutment the piston plunger 15 may coact to forcibly eject the 35 contents of the chamber 14 through the ports 18 or 45 to atmosphere.

In the forms of the invention shown in Figs. 1, 2, 3, 9 and 10 the cylinder of the pump which constitutes the walls of the chamber 14 is in the 40 form of a tube 20 with a diameter somewhat smaller than the over-all diameter of the stem 12 and which is rotatably and slidably journaled in a stem aperture 21 extending axially through that portion of the stem 12 connected with the 45 bowl 10 and continuing axially of the stem through the bottom of the bowl to its egress on the side of the bowl opposite the stem. In the forms of Figs. 4, 6 and 8 the cylinder constituting the walls of the chamber 14 constitutes the 50 stem per se in its entirety.

Referring now particularly to each of the several forms of the invention in succession, in the form of Fig. 1, the plunger 15 is of the piston type and normally lies at the mouthpiece end of a pipe. Here the piston 15 is bridged normally by a draft connection 22 between the chamber 14 and the stem 11. This draft connection is in the form of a slot cut in the end of the tube 20 at its top. It establishes draft connection around 55 the piston 15 between the chamber 14 and the draft opening 23 of the mouthpiece. The piston rod 16 is extended out through the head 19 closing the opposite end of the chamber 14 and provided with a small suspended ring 24 for 60 manual reciprocation of the piston 15. The mouthpiece 11 is threaded on to the adjoining end of the tube 20 to such an extent that it entirely closes the slot 22. A small screw or rivet 65 25 insures proper angular relation of the mouthpiece to the tube 20. The abutment of shoulder 26 against the end 27 of the tube may serve a similar and perhaps cooperative purpose. The outer walls of the stem may be constituted of tubular filler members as 27' between the root 70 75 of the stem 28 integral with the bowl 10 and the

mouthpiece, or it may be a part of the integral connection 28 or the tube 20 may be without covering in this region if desired.

In the bowl of the pipe the guard 29 is suspended in a position closely adjoining the port 17 by means of an annular series of small rods or wires 30 welded to it at their lower ends and welded to an operating ring 31 at their upper ends. The rods 30 bear upon the walls of the bowl with sufficient friction to keep the guard 29 in place when moved axially into position by grasping the ring 31.

The section of Figure 1 shows the parts in the position in which the pipe is smoked. Port 17 to the bowl 10 is open. Port 18 to atmosphere 15 is closed. Port 22 at the opposite end of the chamber 14 is open. The smoke traverses the length of the displacement chamber 14. The moisture and other products usually condensed or otherwise deposited in the stem are collected 20 upon the metallic walls of the tube 20 between the port 17 and the piston 15. So deposited they appear usually as a heavy viscous liquid very dark brown in color. It is convenient to call the liquid a liquid condensate. The other products 25 are usually ash or perhaps small particles of unburned tobacco. At any time it is desired to cleanse the stem of its collected contents, the smoker gives the mouthpiece and connected tube 20 a turn of 180° which results in closing the 30 port 17 and opening the port 18 as shown in Fig. 9. Thereupon he quickly draws the piston 15 the length of the chamber and into contact with the head 19 of chamber 14 whereupon the liquid condensate is placed under pressure and 35 forcibly ejected from the port 18. This relation of the parts is shown also in Fig. 9. The initial movement of the piston 15 from the position of Fig. 1 closes the port 22 communicating with the mouthpiece 11 so that the only possible egress 40 for the contents of the chamber 14 is axially of its length and forcibly through the port 18. But one movement of the plunger completely and thoroughly cleanses the entire chamber. In all the forms of the invention, the close approach 45 and ultimate contact of the piston 15 with either the fixed head 19 or the yieldable combined head and scraper 19' develops within the fluid comprised by the liquid condensate in and of itself a strong fluid pressure, and it is through this 50 pressure and, in the form shown in Figs. 2 and 4, additionally through the sudden outward thrust of the movable abutment 19' by the incline on the piston, that the forcible ejection is 55 achieved. Immediately the plunger may be returned to the normal position of Fig. 1 and the mouthpiece 11 and attached tube 20 turned back through 180° closing port 18 and again opening the port 17 to the bowl. The cleaned pipe is again ready for smoking.

During this smoking the guard disc 29 effectually guards port 17 against the entrance of solid matter. Such small grain solid matter as may once in a great while pass the disc screen 29 is effectually cut off and cut through by the 65 edges of the tube wall 20 at the port 17 when the tube 20 is rotated to open port 18. The turning of the edges at port 17 to the opening of the port 18 presents any such small solid matter at a point where the forcible ejection of the 70 contents of the chamber 14 when plunger 15 brings up against the head 19 causes also the forcible ejection of such occasional solid matter.

However, during the great part of the time the disc 29 precludes the solid matter from reaching 75

the port. This is aided very greatly by the functioning of the disc 29 when it is moved axially of the bowl in ejecting residues of charges thoroughly and in scraping by the edges of the disc 29 residue from the bowl 10. This keeps the bowl so thoroughly cleansed of minor particles of tobacco and ash and particularly burned tobacco that such material does not accumulate at the bottom and therefore is not present to pass by the disc 29. Yet further, because the disc is used the residue of charges is ejected as a body and there is no call for the use of knife blades and the like which not only separate the residue into small portions which may fall within the port 17 but also when used may actually project residue into the port 17. Further yet, in the packing of the pipe, particles of the new charge might enter the port 17 were it not for the guard 29.

In the form of Figs. 3 and 4 the guard is essentially the same as in Figs. 1 and 2. It is to be noted in Fig. 5 where the plan view is shown the draft apertures of the guard 29 are in the form of notches 32 in its edge and not in the form of perforations in its body. This results in confining the draft from the bowl to the edges of the disc guard 29. This gives a better distribution of the draft in the bowl and affords a better burning adjoining the walls of the bowl, especially as the bottom parts of the charge are being burned. Yet further, the notches in the edge are easily cleaned whereas perforations in the body are difficultly cleaned. More to the point, however, the elimination of perforations from the mid-portions of the guard prevents solid matter from dropping into and clogging port 17 of the chamber 14 of the displacement pump. Any other means whatsoever for operating the guard 29 may be used.

The displacement pump of Figs. 2, 3 and 4 is of a different form. The piston 15 and the plunger 16' are of a diameter completely filling and fitting the tube 20, see Figs. 2 and 3, or the bore of the stem per se, see Fig. 4. The chamber 14 is formed by a longitudinal milling out of the main body of the plunger 16' between its ends and all the way from the port 22 of Fig. 2 formed in the tube 20, or the port 22' of Fig. 4 formed in the stem per se to the port 17. The head 19' is in the form of a spring the one end of which is riveted or otherwise fixed to the tube 20 (Fig. 2) or to the bottom of the bowl (Fig. 4) and the other end of which projects yieldably into and closely fits the rectangular cross section of the chamber 14 as shown in Figs. 2 and 3.

In the form of Figs. 2 and 3, therefore, when the mouthpiece 11 and connected tube 20 are turned to close port 17 and open port 18, and thereafter the plunger 16' is pulled out as shown in Fig. 10, the head of the chamber constituted by the spring 19' not only serves as a compression head but scrapes the entire chamber 14 clear of its contents and finally rides up on to the opposite end of the rod, which constitutes the piston 15, forcibly ejecting the contents through the port 18.

The operation otherwise is essentially the same as that in Fig. 1. In this form of the device like that of Figs. 1 and 4 the rotation through 180° to close port 17 and open port 18 and vice versa is regulated by a stop 33 which is fixed to the wall of the bowl 10 and projects into a 180° recess in the end of the tube 20 or the end of the plunger 16' as the case may be. See Figs. 11 and 12.

In the form of Fig. 4 the stop projection 33' is on the end of the plunger 16' and extends into a

180° recess in the bottom of the bowl as is shown in Fig. 12 whereas in the form of Figs. 1 and 2 the arrangement is the reverse with the stop 33 on the bowl and the 180° recess in the tube 20 as is shown in Fig. 11. In the form of Fig. 4 the outer wall of the stem 12 corresponds to the tube 20 of Figs. 1 and 2 and may be an integral continuation of the bowl 10 as stated. Therefore, the valved action brought about by a relative movement of the parts of the stem 12 consists in the rotation of the plunger 16' itself instead of a rotation of the tube 20 within the stem at large. Otherwise the operation of the form of Fig. 4 is precisely the same as that of the form of Fig. 10.

The bowl of this form of Fig. 4 is also different from the bowl of the form of Figs. 1 and 2. It is a metallic bowl instead of a wooden bowl, preferably of cast duralumin. It consists of a relatively thin main shell 34 provided with radial axially extended external ribs 35 for cooling purposes. Outside of these ribs there is superimposed a cylindrical shell 36 of insulating material. Guard and ejecting disc 29 is connected by the wires 39 with and operated by bodily axial withdrawal and replacement of this shell 36 from the ribs of the bowl. The shell thus jointly serves as a manipulator of the guard 29 and an insulator of the metal of the pipe. The tubular stem 12 may or may not be formed integrally as shown with the bowl. The port 22' then consists of a groove formed internally of the tubular stem 12 and the mouthpiece 11 is threaded internally of the outer end of the stem instead of externally as in the other forms.

The form of Fig. 6 consists of quite a different arrangement of parts. In this the axis of the bowl and the axis of the stem 12 instead of being at an angle to each other are in longitudinal continuation. The bowl and stem are connected together for relative axial movement through a complementary taper 37 between the bottom of the bowl and the adjoining end of the stem so that the bowl may be moved axially toward the mouthpiece from the full line position shown to the dotted line position shown. When seated on the taper 37 the bowl 10 makes a draft-tight joint with the same. When the bowl and stem are moved relatively to place the bowl in the dotted line position shown in Fig. 6, the stem is constituted an ejector for the residue contents of the bowl. To this end the disc guard 29 is mounted directly on the end of the stem and secured thereto by small screws 38 or equivalent means. In general plan form the disc guard 29 is of perimeter outline shown in Fig. 5 and has a similar relation to the interior walls of the bowl 10. The bowl 10 is provided with an upturned lip 39 extending the lower edge of the mouth 40 beyond the upper edge whereby ash may not be readily dropped from the open end of the bowl during the smoking.

The displacement pump 13 and its chamber 14 are located in the stem as in the other forms. The piston 15, however, normally lies not at the mouthpiece end of the stem but at the bowl end of the same. It is normally seated in an upward offset 41 of the guard disc 29'. The adjoining end of the stem is provided with ribs 42 which guide it into and out of the chamber 14. The plunger or piston rod 16 extends toward and through the head 19 which closes the mouthpiece end of the stem and is connected with the mouthpiece by a screw 43 or equivalent device such as a pin or a rivet in such manner that when the mouthpiece is grasped and pulled off of the stem 12, the plunger is moved the length of the

chamber 14 up against the head 19. Through radial grooves or apertures 44 at the bowl end of the stem free draft connection is normally maintained with the bowl 10. This connection is valve closed by the plunger 15 in its initial movement axially outwardly into the chamber 14. Through the port 45 in the walls of the chamber 14 immediately adjoining the head 19 the valve connection to atmosphere is established at the mouthpiece end. This valve connection is normally closed by the skirted extension 46 from the mouthpiece 11. This connection may be cylindrical or taper seated as indicated at 47 and constitutes the seating or socketing of the mouthpiece 11 upon the stem 12. It extends sufficiently toward the bowl from the port 45 to effectually seal the port 45 from atmosphere when the mouthpiece 11 is seated upon the stem. A slotted port 22' similar to that used in the forms of Figs. 1, 2 and 4, however, when the mouthpiece 11 is seated, affords draft connection through the port 45 to the mouthpiece as shown. Draft is normally therefore maintained from the bowl to the mouthpiece but when the mouthpiece is withdrawn to pull the plunger 15 into forcible contact with the head 19, the port 45 is opened to atmosphere and the contents of chamber 14 forcibly ejected therefrom.

This form of the invention has particular adaptation to pipes having curved mouthpieces as shown in Fig. 7.

It also has particular adaptation to pipes of the nature of cigarette, cigar or other package type holders as shown in Fig. 8 where corresponding parts are provided with reference numerals corresponding to the numerals in Fig. 6. This form of Fig. 8 differs particularly from the preceding forms in that the bowl 10 is so small that it accommodates but one end of the packaged charge, e. g., a cigarette, cigar or tobacco in wrappers or containers. Otherwise the general arrangement of the parts is the same and their functionings are the same. The ejector ejects the residue of the charge when the bowl 10 and stem are relatively moved to the dotted line position. The pump 13 ejects the contents of the stem when the mouthpiece and the body of the stem are relatively moved in the same manner as in the form of Fig. 6. In this embodiment I have substituted for the taper seating 37 of the forms of Figs. 6 and 7 a coarse screw thread connection according to which by but a fraction of a turn or a turn or two the bowl 10 may be unseated and moved axially toward the mouthpiece 11, as shown in dotted lines, for the purpose of ejecting charge residue.

It is to be noted in connection with all of these forms of the invention disclosed in Figs. 6, 7 and 8, particularly in connection with that shown in Fig. 7, that due to the fact that the draft is always upwardly of the bowl and the stem, the stem has a certain chimney effect and that such a pipe will remain lit therefore for longer periods of time and burn better while being smoked.

My invention is capable of many modifications as herein appears. Those disclosed and all others which come within the purview of the invention per se (as distinguished from the structures specifically subject to the circumstantial terminology I have chosen to describe my invention) are intended to be covered by the annexed claims.

What I claim as new and useful and desire to protect by Letters Patent is:—

1. A pipe comprising a bowl, a stem having a head at one end and a mouthpiece, a piston in

the stem adapted to be reciprocated therein, and means establishing two valved connections, one between the bowl and the stem and another between the stem and the atmosphere independent of the mouthpiece, whereby the bore of the stem may be shut off from the bowl and the reciprocation of the piston may eject directly from the stem to the atmosphere the contents of the stem. 5

2. A pipe comprising a bowl, a stem having a fixed head at one end, a piston in the stem adapted to be reciprocated therein to and from the head, and means establishing a valved connection between the headed end of the stem and the atmosphere independent of the bowl whereby reciprocation of the piston when the valved connection is an open one forcibly ejects the contents of the stem to atmosphere through co-action between the piston and the head. 10 15

3. A pipe comprising a bowl, a stem having a draft chamber provided with a fixed abutment at one end, a piston in the stem adapted to be reciprocated therein toward and from said abutment, and relatively movable parts including said stem controlling a valve port from the stem to the atmosphere substantially at the abutment 20 25 and independent of the bowl, whereby reciprocation of the piston may forcibly eject the contents of the stem through the port to atmosphere through co-action with said abutment.

4. A pipe having a bowl and a draft mouth-piece and a displacement force pump between the bowl and the mouth-piece through the chamber of which pump draft connection is normally effected between the bowl and the mouthpiece, which pump has a valved ejection port to atmosphere and a fixed abutment adjacent said port and means to operate the pump to forcibly eject the contents of said chamber through said port by coaction with said abutment. 30 35

5. A pipe comprising a bowl and a mouth-piece 40 and a force pump intermediate the bowl and the mouth-piece through the chamber of which, draft connection is effected between the bowl and the mouth-piece, a fixed head at one end of said pump chamber, and a valved port to atmosphere 45 from the pump chamber adjacent said head through which the contents of the pump chamber may be forcibly ejected through the operation of the pump, which port is on the upper side of said chamber. 50

6. A pipe comprising a bowl and a mouthpiece and a pressure force pump intermediate the bowl and the mouthpiece through the chamber of which, draft connection is effected between the bowl and the mouthpiece and which receives the liquid condensate, and a normally closed valved port to atmosphere from the pump chamber through which the liquid condensate of the pump chamber may be forcibly ejected under pressure through the operation of the pump, and a second 60 65 valved port connecting the chamber with the bowl. 70

7. A pipe comprising a bowl, a mouthpiece, a displacement pressure force pump through the chamber of which, draft connection is effected 65 between the mouthpiece and the bowl, and a valved port at one end of said pump chamber through which the liquid condensate of the chamber may be forcibly ejected under pressure to atmosphere through the operation of the 70 pump, and a valved connection at the other end of the chamber to the bowl of the pipe. 75

8. A pipe comprising a bowl, a mouthpiece, a displacement pressure force pump having a chamber by which draft connection is effected 75

- between the bowl and the mouthpiece, a port connecting the pump chamber with the bowl and a port connecting the pump chamber with the atmosphere, a fixed head adjacent said port to atmosphere, together with means for opening and closing the ports, and means for operating the pump in cooperation with said head to eject under pressure through said port the liquid condensate of said chamber.
9. A pipe comprising a bowl, a mouth-piece, a displacement force pump having a chamber by which draft connection is effected between the bowl and the mouth-piece, a port connecting the pump chamber with the bowl and a port connecting the pump chamber with the atmosphere, a fixed abutment at the end of said pump chamber adjacent the port to atmosphere and means for closing the port to the bowl when the port to atmosphere is opened.
10. A pipe comprising a bowl, a mouth-piece, a displacement force pump having a chamber by which its draft connection is effected between the bowl and the mouth-piece, a port connecting the pump chamber with the bowl and a port connecting the pump chamber with the atmosphere, a fixed abutment at the end of said chamber adjacent the port to atmosphere and sliding valve means to close and open the ports.
11. A pipe comprising a bowl, a stem, a mouth-piece, a displacement pump having a chamber by which its draft connection is effected between the bowl and the mouth-piece, a port connecting the pump chamber with the bowl and a port connecting the pump chamber with the atmosphere independent of the mouthpiece, and sliding valve means comprising relatively movable parts co-acting with the pipe stem to open and close the ports.
12. A pipe comprising a bowl, a mouthpiece and a force type displacement pump having a displacement chamber through which draft connection between the bowl and the mouthpiece is effected, a fixed head at the mouthpiece end of the pump chamber, a valved port between the bowl end of the pump chamber and the bowl, and a valved port between the mouthpiece end of the pump chamber and the atmosphere arranged on the side of said head toward the bowl.
13. A pipe comprising bowl, mouth-piece and a reciprocating force type displacement pump having a displacement chamber through which draft connection is effected between the bowl and the mouthpiece, said chamber having a fixedly headed end and the piston rod of the pump extending through said headed end for operation of the pump from the exterior of the chamber, and a valved connection to atmosphere adjacent said head of the chamber whereby upon operation of the piston to said head the contents of the chamber are forcibly ejected to atmosphere between the piston and the head.
14. A pipe comprising a bowl, mouth-piece and a reciprocating type displacement pump having a displacement chamber through which draft
- connection is effected between the bowl and the mouthpiece, said chamber having a headed end and a piston rod of the pump extending through said headed end for operation of the pump from the exterior of the chamber, and a valved connection to atmosphere adjacent said head of the chamber whereby upon operation of the piston to that head the contents of the chamber are forcibly ejected to atmosphere between the piston and the head, and said pump being embodied in the pipe stem in axial alignment with the mouth-piece.
15. In a pipe comprising a bowl, a mouth-piece, a displacement pump having a cylindrical displacement chamber through which draft connection is effected between the bowl and the mouth-piece and comprising a metallic tube interconnecting the bowl and the mouth-piece and rotatable relatively to the bowl, and ports in the pipe bowl between the bowl space and the chamber on the one hand and the chamber and the atmosphere on the other under valved control through the rotation of said tube.
16. A pipe comprising a bowl, a mouth-piece and a piston pressure pump interconnecting the bowl and the mouth-piece having a chamber through which draft connection is effected from the bowl to the mouth-piece and comprising a cylinder in the form of a tube interconnecting the bowl and the mouthpiece, and a valved connection between such chamber and the atmosphere controlled by relative movement between the tube on the one hand and the bowl on the other, said piston pump including means adapted to create a pressure to force the chamber contents through said connection.
17. A pipe comprising a bowl and a mouth-piece, a displacement type pressure force pump having a displacement chamber through which draft connection is effected from the bowl to the mouthpiece and provided with relatively movable parts through which the liquid condensate within the chamber is put under pressure, together with a port to atmosphere communicating with that portion of the chamber in which the liquid pressure is developed wherethrough the liquid condensate may be ejected under pressure to atmosphere.
18. A pipe comprising a bowl and a mouth-piece, a displacement type pressure force pump having a displacement chamber through which draft connection is effected from the bowl to the mouthpiece and provided with relatively movable parts through which the liquid condensate within the chamber is put under pressure, together with a port to atmosphere communicating with that portion of the chamber in which the liquid pressure is developed wherethrough the liquid condensate may be ejected under pressure to atmosphere, one of said relatively movable parts comprising a piston, and the other a co-acting head at the bowl end of the pipe.

JOHN P. TARBOX.
